US00D518720S

(12) **United States Design Patent** (10) **Patent No.:** **US D518,720 S**
Gratz (45) **Date of Patent:** **** Apr. 11, 2006**

(54) **TWO-SIDED ROLL SUPPORT WITH
MULTIPLE RIBS**

(75) Inventor: **Jeffrey J. Gratz**, Hartland, WI (US)

(73) Assignee: **Fibreform Containers, Inc.**,
Germantown, WI (US)

(**) Term: **14 Years**

(21) Appl. No.: **29/220,747**

(22) Filed: **Jan. 5, 2005**
